Primary Examiner — Tamara L Hahn(74) *Attorney, Agent, or Firm* — Procopio, Cory, Hargreaves & Savitch LLP(57) **CLAIM**

The ornamental design for a forklift attachment, as shown and described.

DESCRIPTION

FIG. 1 is an elevational view of the forklift attachment shown in condition of use;

FIG. 2 is a perspective view of the forklift attachment.

FIG. 3 is a front elevational view of the forklift attachment.

FIG. 4 is a rear elevational view of the forklift attachment.

FIG. 5 is a left side elevational view of the forklift attachment.

FIG. 6 is a right side elevational view of the forklift attachment.

FIG. 7 is a top plan view of the forklift attachment; and, FIG. 8 is a bottom plan view of the forklift attachment.

The broken lines shown in the drawings depict portions of the forklift attachment that form no part of the claimed design. The broken line showing of the trash buggy and dumpster in FIG. 1 depict environmental elements that form no part of the claimed design.
